UNITED STATES PATENT OFFICE.

EDWARD P. FREDERICK, OF ST. LOUIS, MISSOURI, ASSIGNOR OF ONE-HALF
TO JAMES D. HOUSEMAN, OF ST. LOUIS, MISSOURI.

ELECTRIC-RAILWAY RAIL-BOND.

SPECIFICATION forming part of Letters Patent No. 703,779, dated July 1, 1902.

Application filed March 20, 1902. Serial No. 99,105. (No model.)

To all whom it may concern:

Be it known that I, EDWARD P. FREDERICK, a citizen of the United States, residing at the city of St. Louis, in the State of Missouri, have 5 invented certain new and useful Improvements in Electric-Railway Rail-Bonds, of which the following is a full, clear, and exact description, reference being had to the accompanying drawings, forming part of this 10 specification.

My invention relates to a rail-bond adapted for use in spanning the gap between abutting sections of railway-tracks to provide for the passage of electric current from one rail to 15 another.

My invention consists in features of novelty hereinafter fully described, and pointed out in the claims.

Rail-bonds of the nature to which my invention relates as heretofore constructed have most commonly been of wire and had their terminals attached to the rail beneath the fish-plates that united the rails, making it a difficult matter to replace them with new ones 20 from time to time as necessity demanded or to repair them when necessary, owing to the requirement of removing the fish-plate to obtain access to the bond. Another objection to a bond so concealed has been the difficulty 25 of determining the condition of the bond and the fact of whether a leakage of current existed or not or whether there was non-contact of the terminals with the rail, a difficulty that has resulted in great annoyance, expense, labor, and loss of current and time 30 upon all electric railways equipped with the ordinary wire bond. In all railway-tracks there is a constant tendency of the bonds to become loosened and imperfect contact occasioned from time to time by reason of vibration 35 and expansion and contraction of the rails, and for this reason it is of the utmost importance that a bond be used that may be readily applied or removed and readily tightened to the rails to secure perfect contact when it may become imperfect and also to 40 provide a construction of bond wherein all of the contacting surfaces throughout the bond and its terminal attachments to the 45 rails will be as perfect as possible.

It is the object of my invention to provide

a bond in which such features will be embodied and in which the objectionable features of the old forms of bonds will be overcome.

55

Figure I is a side view of a pair of railway-rails with one of my improved bonds applied thereto and shown partly in longitudinal vertical section. Fig. II is a top or plan view of the rails and bond, shown partially in horizontal longitudinal section. Fig. III is a perspective view of one of the terminal sockets of my bond. Fig. IV is a cross-sectional view taken on line IV IV, Fig. III. Fig. V is a perspective view of one of the bushings interposed between the railway-rails and the terminal couplings. Fig. VI is a detail view of one of the strand conductors. Fig. VII is a sectional view of a modification of the terminal couplings and bushings. Fig. VIII is a perspective view of the washer used upon the bushing shown in the modified construction in Fig. VII.

A designates two meeting railway-rails joined by fish-plates B, containing bolts C. 75 In the webs of the rails A are orifices 1, preferably tapered, as seen in Figs. II and VII.

2 designates wire-strand conductors, preferably having a central core of one or more copper wires and encircled by a series of iron 80 wires, thereby providing the proper conducting qualities for the electric current and flexibility and elasticity in the bond at a less cost than in the use of a strand of copper wires alone. The conductors may, however, be 85 composed entirely of copper or iron or any other suitable material.

4 designates terminal couplings provided with chambers 5, in which the terminals of the conductors 2 are located, as seen in Figs. I and 90 II, the terminal wires of the conductors being spread within said couplings and being embedded in a filling 6, of soft metal, such as babbitt, that is introduced thereinto in a molten condition. In the rear of each terminal 95 coupling 4 is a pocket 7, that has communication with the terminal receiving-chamber 5, and in the forward side of each socket are a series of pockets 8, that have communication with the chamber 5. The pockets 7 and 8 are all adapted to receive the soft metal introduced into the terminal couplings, and in

them the soft metal is designed to shrink, by reason of the chilling action upon such metal being greater in the walls of the sockets than it is in the interior of the chamber 5. By 5 reason of such shrinkage in the pockets the soft metal is drawn into close contact with the inside of the coupling-walls to prevent the formation of crevices or spaces between the soft metal and the insides of said walls 10 when the soft-metal filling 6 is introduced, thereby producing a close contact between the walls of the couplings and the soft metal within the chamber 5, that will provide perfect circuit-way from the conductor into the 15 terminal couplings. Each terminal coupling 4 is provided with an arm 9, that contains an aperture 10, preferably tapered, as shown in Fig. II.

11 designates bushings, of soft metal, preferably copper or aluminium, that are interposed between the terminal couplings, the two ends of which are preferably tapered, as seen in Figs. II and V, to fit the orifices 1 in the webs of the rails A and the apertures 10 25 in the terminal coupling-arms 9.

12 designates boss-arms that extend outwardly from the bushings 11 and occupy positions between the rail-webs and the arms of the terminal couplings and serve to steady 30 the terminal sockets and hold them in alignment with the rail-webs for the purpose of securing the most perfect connection of the bond to the railway-rails and avoidance of leakage by improper connection.

35 13 designates bolts that pass through the terminal coupling-arms 9, bushings 11, and rail-webs and serve as fasteners to tightly secure said parts to the railway-rails and provide the close-fitting connection whereby is 40 provided efficient passage of electric current from the rails to the conductors and therefrom to the abutting rails. By the use of the bolts 13 and nuts therein I am enabled to draw the terminal couplings much more tightly to the 45 rails than is permissible in the use of riveted connections, the tendency of which is to loosen the connection the more the riveting process is continued.

In Figs. VII and VIII, I have shown a modification wherein the terminal couplings 4^a have the bushings 11^a formed integral therewith and the boss-arms 12 are dispensed with. In their stead a washer 12^a, of soft metal, preferably copper or aluminium, provided with bosses 12^b, is seated on the bushings 11^a between the terminal coupling-arms and the web of the railway-rail. The terminal couplings in this construction are held to the rails by bolts 13^a in a similar manner to 60 that hereinbefore described.

I have shown two conductors used in my bond, and prefer to use this number ordinarily, as it has been found to furnish satisfactory results. I do not limit myself to the use of any

particular number of conductors, however, as 65 one or any greater number may be used.

By making the bushings 11, that are interposed between the terminal couplings and the rails to which the bonds are affixed, of a soft metal, preferably copper or aluminium, that 70 is of slight resistance and yielding, it will be seen that I am enabled to draw said bushings tightly into the rails in such manner that they are clamped between the arms 9 of the couplings 4 and rails to secure the most efficient contact between the terminal couplings and the rails, this being particularly the result of the yielding nature of the soft metal of which the bushings are formed. The same applies to the washers 12^a, which are interposed between the terminal coupling-arms 75 and the rails and are, like the bushings 11, of soft metal.

I claim as my invention—

1. In a railway-rail bond, the combination 85 of a conductor, and chambered terminal couplings having pockets in the wall thereof adapted to receive a filling introduced to fill the chambers of the couplings, substantially in the manner and for the purpose set forth. 90

2. In a railway-rail bond, the combination of a conductor, terminal couplings provided with pockets and having chambers therein in communication with said pockets, and a soft-metal filling in said terminal couplings in 95 which said conductors are embedded, substantially as and for the purpose set forth.

3. In a railway-rail bond, the combination of a conductor, terminal couplings in which said conductor is seated and held, bushings 100 adapted for introduction into the webs of the railway-rails at the rear of said terminal couplings, and bosses located between said terminal couplings and the webs of the rails, substantially as described. 105

4. In a railway-rail bond, the combination of a conductor, terminal couplings in which said conductor is seated and held, arms carried by said terminal couplings, bushings positioned in said arms and adapted to enter 110 the webs of the railway-rails, and means for attaching said terminal couplings and bushings to said rail-webs, substantially as described.

5. In a railway-rail bond, the combination 115 of a conductor, terminal couplings in which said conductor is seated and held, arms carried by said terminal couplings, bushings having tapered ends adapted to seat in said arms and in said rail-webs, and bosses carried by 120 said bushings positioned between said coupling-arms and said rail-webs, substantially as described.

EDWARD P. FREDERICK.

In presence of—

E. S. KNIGHT,
M. P. SMITH.
